GUY P. THURBER, OF PITTSBURGH, PENNSYLVANIA.

AUTOMATIC TRAIN-CONTROLLING SYSTEM.

1,193,635.

Specification of Letters Patent.

Patented Aug. 8, 1916.

Application filed March 31, 1913. Serial No. 757,853.

To all whom it may concern:

Be it known that I, GUY P. THURBER, a citizen of the United States, and a resident of Pittsburgh, in the county of Allegheny and State of Pennsylvania, have invented 5 certain new and useful Improvements in Automatic Train-Controlling Systems, of which the following is a specification.

The present invention relates to train control systems and especially the type of systems in which a closed electric train-circuit normally passing through a section of track is used to hold train controlling devices inoperative, and which, when ruptured, automatically releases said train controlling devices and permits them to operate to stop the train or otherwise exercise a control over the same.

The object of the present invention is to 20 simplify the construction of the parts as much as possible and to reduce the number of electric circuits utilized in effecting a proper control of the train.

The invention accordingly consists in the 25 employment of a fluid pressure train controlling circuit, and a normally closed charged electric train-circuit normally completed through the traffic track, together with an electro-magnetic device having 30 valve means which is interposed in the fluid circuit and in the electric circuit and exercises control over both circuits. Preferably the electromagnetic device has two armatures under its control, one of these armatures being provided with a valve which controls 35 the fluid pressure system, and the other armature forming a circuit breaker in the electric circuit.

Other features of construction, arrangement of parts, and combination of elements 40 will appear as the specification proceeds.

In the accompanying drawings the invention is disclosed in a concrete and preferred form, but changes may be made without departing from the spirit and scope of the 45 invention.

In the said drawings: Figure 1 is a dia- 50 grammatic view of the system with the controlling unit shown in section, the parts being in the position they assume when the electric circuit is closed. Fig. 2 is another sectional view of the controlling unit, with parts of the electric circuit, the parts being shown in the position they occupy when the 55 electric circuit is ruptured or when the cut-out valve is moved to a position where the

automatic control of the train is eliminated. Fig. 3 is a broken detail view of a portion of the cut-out device, taken substantially on the line 3-3 of Fig. 2.

60

Similar characters of reference indicate corresponding parts in the several views.

In the construction illustrated in the drawings 10 indicates the traffic track divided by suitable insulation 11 into blocks 65 in a well-known manner. Adjoining blocks are connected by means of a jumper circuit, indicated by 12, which jumper circuit is controlled by a relay 13 and an armature or circuit breaker 14.

70

15 indicates the line wires for controlling the relay 13 in a well-known manner, the general operation being that when a train occupies a near-by block, the relay 13 is de-energized to rupture the jumper circuit so 75 that it is impossible for the train controlling circuit, to be described, to be completed through the traffic track, thereby causing it to be ruptured.

25 indicates an electro-magnetic device 80 which controls both the fluid pressure circuit and the electric circuit. In the form shown the electric circuit extends from the battery 26, along conductor 27, through conductor 24, interposed in the draw bar insulation 23, to the plates 22 surrounded by the insulation 21 of truck 20, thence along conductor 28 to the armature or circuit breaker 29, thence along conductor 30 to the electro- 85 magnetic device 25, and thence by means of conductor 17 to the wheels 19 of the truck 20, along the rails 10, through the jumper circuit and armature 14 to the other side of the insulation 11, and thence to the drivers 18 of the locomotive and along the conductor 16 back to battery 26. The flow of current through the coil in the electro-magnetic device 25 energizes said device and when so 90 energized serves to maintain the automatic control ineffective. As soon, however, as this circuit is broken, due either to an interruption in the continuity of the rails or to the rupture of the jumper, the electro-magnetic device will become de-energized and it then serves to render the automatic control 95 operative.

Considering now the construction of the so-called controlling unit, the same preferably consists, as shown, of a substantially cylindrical member or casing 31, in one end 110 (here shown as the lower end) of which is mounted the electro-magnetic device, and

in the opposite end of which is mounted the 5
brake valve 32 or other device for directly
controlling the train. Interposed between
the electro-magnet in the one end of the cas-
ing and the brake valve in the opposite end of
the casing is a pressure-actuated device for
operating the brake valve, and valve mecha-
nism under the control of the electro-magnet
for governing flow of actuating fluid to
10 the pressure-actuated device. In the case
illustrated, the pressure-actuated device is
the piston 33 working within a piston cham-
ber 34 formed in the body of the casing, and
the valve mechanism consists of a stem
15 35 upon which is engaged an inlet valve 36
and an exhaust valve 37. The inlet valve
controls flow of actuating fluid from an in-
let chamber 38 past the valve seat 39, and
passage 40, to the piston chamber, while the
20 exhaust valve when open permits flow from
the piston chamber back through passage
40, and exhaust valve seat 41, into an ex-
haust chamber 42 and out through exhaust
port 43. The valve stem is attached to the
25 armature 44 of the electro-magnet, and a
spring 45 is preferably provided for shift-
ing the valve stem to carry the valve to the
reversed position when the magnet is de-
energized.

30 The brake valve, as here illustrated, con-
sists of an inlet chamber 46 and an exhaust
chamber 47, with the two chambers sepa-
rated by a partition 48, having a valve seat
49 therein which is arranged to be engaged
35 by the valve 50. Valve 50 is connected with
the piston 33 so as to be operated thereby,
and such connection, as here shown, consists
of a stem 51 directly attached to the piston.
The spring 52 is preferably provided for
40 shifting the piston to carry the valve 50 to
the open position.

45 The brake system or other part of the nor-
mal train controlling means is preferably
utilized for actually stopping or controlling
the movement of the train. In the present
instance the controlling unit is shown as
50 connected with the brake system so as to
control the train through the medium of
the brake system. In the illustration, 53 in-
dicates the train line or similar part of the
fluid pressure circuit of the brake system,
55 and the brake valve end of the controlling
unit is connected with the train line by suit-
able piping 54. In order that the control-
ling unit may, when desired, be disconnect-
ed from the brake system so as to render
60 the automatic stopping system inoperative,
there is preferably interposed a so-called
cut-out valve 55 in this line of pipe connec-
tions between the train line and the con-
trolling unit. This cut-out valve is illus-
trated more or less diagrammatically, and
65 the same is shown to be provided with a
rotatable valve member 56 which is formed
with a port 57 arranged when the valve is

in the position shown in Fig. 1, to register
with the pipe connection 54 leading to the
brake valve. This rotatable valve member
is preferably made hollow, as indicated at
58, and the fluid under pressure is led up
70 through the center of the valve body in the
manner indicated in Fig. 3. The fluid under
pressure from the train line thus normally
flows through piping 54 up through
75 the hollow center of the valve body and out
through the port 57 and piping 54 into the
inlet side 46 of the brake valve (Fig. 1).
The fluid for actuating the pressure-actuated
device 33 may be supplied from any
80 suitable source. In the illustration the ac-
tuating fluid is the fluid under pressure in
the train line. Instead of taking this pres-
sure direct from the train line it is prefer-
ably taken through the intermediary of
85 the cut-out valve so that when communica-
tion between the brake system and the con-
trolling unit is cut off, flow of actuating
fluid to the pressure-actuated device will
also be cut off. A conduit 59, therefore, in
90 the present illustration, conducts the actu-
ating fluid from the cut-out valve to the
passages leading to the pressure-actuated
device. The valve body 56 is, for the pur-
pose of controlling this flow to the passages
95 aforesaid, preferably provided with the ad-
ditional port 60 which, when the valve is in
the normal position shown in Fig. 1, regis-
ters with conduit 59.

100 In order that the operation of the inven-
tion will be fully understood, it will be as-
sumed that everything is in proper running
order, and that the electric train controlling
circuit is being properly completed through
105 the traffic tracks and through the jumpers
when passing from one insulated block into
another. Under such conditions the elec-
tro-magnet 25 is energized and therefore
acts, in the manner indicated in Fig. 1, to
110 hold the circuit closer 29 in closed position,
and to hold the exhaust valve 37 of the
valve mechanism in closed position. Fluid
under pressure in the train line flows
115 through pipe connections 54 and the cut-
out valve into the inlet side of the brake
valve 32. This fluid under pressure from
the train line also flows through conduit 59
past the inlet valve 36 and through passage
120 40 into the piston chamber 34, where, acting
upon the piston therein, it forces the said
piston over, thereby closing the valve 50
against its seat and preventing any escape
125 of the train line pressure through the brake
valve. If, now, for any reason the circuit
is ruptured, say, by the train encountering
a broken jumper when passing from insu-
lated block into another, the electro-magnet
25 will be deenergized and will drop its ar-
mature 44 and cause the circuit breaker to
be opened. This condition is illustrated in
130 Fig. 2, wherein it will be noted that the re-

lease of the armature 44 permits the valve stem 35 to move under the influence of gravity or spring 45, until the inlet valve 36 engages with its seat 39. This cuts off 5 any further flow of actuating fluid to the pressure-actuated device, and since the movement of the valve stem has also opened exhaust valve 37, the fluid under pressure which formerly occupied the piston chamber 10 is now permitted to escape back through the passage 40 past the now open exhaust valve, and out through the exhaust port 43. This release of the fluid acting upon the piston 33 permits said piston to descend by 15 gravity, assisted by spring 51, thereby removing valve 50 from its seat. The brake valve being now open, the train line pressure is free to escape out through the exhaust port 61. This release in the train line 20 pressure causes an application of the brakes to be made in the usual way.

Since the circuit breaker 29, which is under the control of the electro-magnet 25, serves, in the manner before described, to 25 control the circuit through the electro-magnet, it will be clear that when the said magnet is once deenergized, it will not, on account of this rupture of the circuit by the circuit breaker, be able to again restore its 30 own circuit. Means are therefore preferably provided whereby a restoring circuit may be completed through the electro-magnet independent of that circuit which is controlled by the circuit breaker. This restoring 35 circuit may be controlled by an ordinary circuit closing key. Preferably, however, I incorporate in the cut-out valve circuit closing mechanism by which the circuit through the electro-magnetic device may be restored.

40 In the illustration this circuit closing device is shown in the form of a segment 62 which is carried by the movable member of the cut-out valve, and acts when in the proper position, to bridge the relatively stationary contacts 63 and 64. Extending from contact 63 is a conductor 65 leading to one terminal of the electro-magnet, and extending from the other contact 64 is a conductor 66 which in the present illustration makes connection with the conductor 28. When, therefore, the engineer desires 45 to restore the circuit through the electro-magnetic device, he simply turns the rotatable member of the valve body until the segment 62 bridges the contacts 63 and 64. While this takes place, the valve circuit is completed: from contact 64, across segment 62, to contact 63, thence by conductor 65, to the electro-magnet, thence through conductor 17, to the insulated trucks of the tender, along the rails to the wheels 18, through the conductor 16, to the battery, thence through the conductor 27, conductors 24 and 22 and conductors 28 and 66, to contact 64. This 50 circuit has the effect of energizing the elec-

tro-magnet, and said electro-magnet when so energized picks up the circuit breaker 29, thereby restoring the normal electric running circuit.

When the plate 62 spans the space between the contacts 63 and 64, the port 57 of the cut-out valve will restore communication between the pipe 54 and the pipe 59, so that as the electro-magnet 25 is reenergized air will flow back to the chamber 38 75 and thence by means of the passages described to the chamber 34, and will, by acting against the piston 33, close the brake valve 50. The cut-out valve may now be restored to its original position, indicated 80 in Fig. 1, and air admitted to the chamber 46, so that when the electro-magnet 25 is again deenergized, the air brake system will again be operated to stop the train.

When it is desired to cut the automatic 85 control system wholly out of operation, the movable member of the cut-out valve is simply turned into the position substantially as indicated in Fig. 2, wherein it will be seen that the ports 57 and 60 in the said 90 member have been carried out of register with the pipe connections leading to the controlling unit, thereby cutting off any further flow of fluid to the controlling unit. In this position also it will be noted that 95 the segment 62 which forms a part of the restoring circuit has been carried to such a point as not to bridge the contacts 63 and 64.

If desired, means may be provided for indicating to the engineer when the automatic 100 control system is operative, so that he may know whether or not he can depend upon the automatic system to take control of the train in an emergency. I have here illustrated a means for this purpose in the form 105 of a signal lamp 67 which is arranged to burn so long as the automatic control system is operative. The circuit for this lamp is here shown as from battery 26, through conductors 27, 28, 66 and 68 to a contact 69, 110 through a segment 70 on the rotatable valve body, and a coöperating contact brush 71, and by a conductor 72 to the lamp, and thence by a conductor 73 and leg 16 to the return side of the battery. The segment 70 115 is provided so that when the cut-out valve is turned to the cut-out position shown in Fig. 2, the signal circuit will be interrupted at the contacts 69 and 71. This segment 70 is preferably of such a length as to bridge the 120 contacts 69 and 71 when the cut-out valve is in normal running position, and also when the cut-out valve is in the circuit restoring position.

What is claimed, is:

1. In a system of train control, the combination with train controlling means, of a fluid actuated device which when supplied with fluid holds said train controlling means inoperative, a magnet valve which when en- 130

ergized supplies fluid to the fluid actuated device, a normally closed charged electric train controlling circuit normally completed through the traffic track normally holding 5 said magnet valve energized, and a circuit breaker in said circuit normally held closed by said magnet valve.

2. In a system of train control, the combination with the fluid pressure brake system, of a train pipe venting device, an electro-magnetic-valve normally acting to restrain the operation of the train pipe venting device when energized, a normally closed charged electric train controlling circuit 10 normally completed through the traffic track normally holding said magnet valve energized, and a circuit breaker in said circuit constituting an armature of the electro-magnetic-valve and normally held closed 15 thereby.

3. In a train controlling system, the combination of a train pipe, a fluid actuated valve controlling said train pipe, a normally closed charged electric train-circuit, normally completed through the traffic track, and an electro-magnetic-valve interposed in 25 the electric circuit and exercising control over the electric circuit and over the fluid actuated valve.

4. In a system of train control, the combination of a fluid pressure train controlling system, a normally closed charged electric train-circuit, normally completed through the traffic track, a valve in said fluid pressure circuit, an electro-magnetic device in 30 said electric circuit, a circuit breaker in said electric circuit constituting an armature for the electro-magnetic device, and a plunger, in said electro-magnetic device, connected to 35 the valve aforesaid.

5. In a system of train control, the combination of a fluid pressure train controlling system, a normally closed charged electric

train-circuit, normally completed through the traffic track, an electro-magnetic device in said electric circuit, and two armatures under the control of said electro-magnetic device, one constituting a circuit breaker for the electric circuit and the other constituting a valve for the fluid circuit.

50

6. A controlling unit for an automatic train controlling system, comprising, a brake valve arranged for connection with a fluid pressure brake system, a fluid-pressure-actuated device below the brake valve and connected therewith for operating the same, valve mechanism below the pressure actuated device controlling flow of actuating fluid to and from such pressure actuated device, an electro-magnetic device below the valve mechanism and operatively connected therewith, and a circuit breaker below the electro-magnetic device, under the control of such device and arranged to control a circuit therethrough.

65

7. In a system of train control, the combination of train controlling means, a fluid actuated brake controlling means, a magnet-valve which when energized normally supplies fluid to hold said brake controlling means inoperative, a normally closed charged electric train controlling circuit normally completed through the traffic track normally holding said magnet-valve energized, and a circuit breaker in said circuit 70 constituting an armature of said magnet-valve and normally held closed by said magnet-valve.

75
